UNITED STATES PATENT OFFICE.

BRUCE BORLAND, OF CHICAGO, ILLINOIS.

LOCK.

1,037,115.

Specification of Letters Patent. Patented Aug. 27, 1912.

Application filed May 6, 1907. Serial No. 372,114.

To all whom it may concern:

Be it known that I, BRUCE BORLAND, a citizen of the United States, residing at Chicago, in the county of Cook and State 5 of Illinois, have invented certain new and useful Improvements in Locks, of which the following is a specification, reference being had therein to the accompanying drawing.

10 My invention relates to locks, and especially to locks adapted to be used as safe-deposit locks, and the main object is to provide a system in which a series of locks set to different combinations are operated by 15 a common intermediary, preferably in the nature of a compound key, between the locks and operator, other objects being also apparent from the disclosure.

My invention consists in the organizations, arrangement, and combinations of 20 parts hereinafter described and pointed out in the claims.

The accompanying drawings illustrate an exemplification of my invention in a practical and preferred form, and in the drawings—

Figure 1 is a central sectional view of an embodiment of the present invention showing the lock applied to a door and with 30 the compound key partially withdrawn; Fig. 2 is a similar view with the compound key inserted in the lock; Fig. 3 is a plan view of the compound key with the cover removed showing the parts in locked position, certain of the parts being in section; Fig. 4 is a similar view of the lock showing the parts in locked position; Figs. 5, 6, 7, and 8 are detail sectional views showing the various parts of the compound key in 40 unguarded position; Figs. 9, 10, 11, 12 and 13 are detail sectional views showing various parts of the lock in unguarded position, together with certain associated parts of the compound key in position with relation thereto; Fig. 14 is a top plan view partly in section of the compound key with cover removed showing the relation of the parts in 45 the unlocked position, with the keys therefor in section; Fig. 15 is a detail view of the bolt-gears of the lock in unlocked position with an associated part of the compound key in 50 position with relation thereto; Figs. 16 and 17 are detail views of the two-part tumblers of the lock in unlocked position and with 55 associated parts of the compound key in position with relation thereto; Fig. 18 is

a plan view of the lock showing parts of the resetting device, it being understood that the parts shown in Figs. 15, 16 and 17 have been lifted out of the casing of 60 Fig. 18; Fig. 19 is a detail plan view of the lock in unlocked position for resetting the lock upon a new combination, certain of the parts being removed for clearness of illustration; Fig. 20 is a similar view of the same 65 parts in position when the manager's key is thrown to its first position in resetting upon a new combination; Fig. 21 is a similar view of the same parts in relocked position to unlock the manager's key in resetting upon a new combination; Fig. 22 is 70 a similar view of the same parts in position when the manager's key is thrown to disengage the parts of the tumblers in resetting on a new combination; Fig. 23 is a 75 similar view of the same parts in position when a new key is inserted and the manager's key is thrown back to reengage the parts of the tumblers upon a new combination; Fig. 24 is a similar view of the same parts in 80 position when the lock is unlocked by a new key, and before the manager's key is returned to original position; Figs. 25, 26 and 27 are views of different operating keys, the key of Fig. 25 being used in the present description as a guard's key and the other keys 85 being different depositor's keys; Fig. 28 is a view of the manager's key; and Fig. 29 is a view of a series of safe deposit boxes supplied with the locks of this invention 90 and adapted to be operated by the common compound key hereof.

In carrying out my invention I employ a series of locks, each preferably set for a different key, and an intermediary preferably in the nature of a compound key adapted to be temporarily assembled with each of said locks and to receive the respective key or keys for operating the said locks.

In practice the locks are preferably all of 100 the same construction, and so a detailed description of the organization and mode of operation of one will answer for all.

The lock comprises a casing 30 provided with a cap or cover 31 held thereon by suitable screws engaging lugs 32, the whole being secured to a door 33 by suitable screws 34, as shown in Fig. 2, passing through screw-holes 35 into the door. The bolt 36 is provided with a shoulder or offset 37 inside the casing from which the upper and lower bolt-tails 38 and 39 extend. The bolt-

gears 40 and 41 mesh with each other and with rack-teeth on the tails; the gear 40 is mounted on a stub 42 on the cap 31 as shown in Fig. 2, and the gear 41 is mounted in a cup 43 on the case. The cup 43 is cut away and flattened to allow the bolt-tails to move, and the bolt-tails are cut away to clear the lugs 32, as shown in Fig. 4. I employ a plurality of two-part tumblers to control the bolt, and in the present embodiment of the invention these tumblers consist of co-acting pivoted members in the form of intermeshing spur-gears; I have shown two tumblers for convenience of illustration, it being of course understood that any suitable number may be employed. The gears 44 and 45 constituting the main or gate parts of these tumblers are mounted upon a hub 46 carried in the casing in a manner hereinafter described, and the gears 47 and 48 constituting the supplemental parts of the tumblers are mounted in the cup 43, the arrangement being such that the parts 44 and 47 coöperate and the parts 45 and 48 coöperate as shown in Figs. 10, 11, 16 and 17, it being understood that Figs. 10 and 11 are separated sectional views showing these tumblers and associated parts and that Figs. 16 and 17 show these tumblers lifted out of the case of Fig. 18 in which the parts are superimposed one upon the other, as shown in Figs. 2 and 4. An additional gear 49 is located in the cup 43 behind the gear 48 for a purpose hereinafter described. The parts of these tumblers may of course be set in a variety of positions with respect to each other, and the main parts 44 and 45 are provided with gatings 50 for the reception of the fence 51 on the bolt 36, so that when the tumblers are moved to aline their gatings in the path of the fence, the bolt may be retracted by turning the bolt-gears 40 and 41, it being of course understood that the tumblers normally stand with their gatings variously out of the path of the fence, as shown in Fig. 4 for example.

The gears 47 and 48 are provided with blank spaces as shown in Figs. 16 and 17, and when the parts are assembled in locked position these blanks are alined and are in contact with the teeth of the gears 44 and 45 so that they cannot be turned farther to the right. If either of the gears be displaced, as by any person attempting to pick the lock, it can be returned to normal position by merely rotating it to the right until its blank comes into contact with the teeth of the associated gear 44 or 45, which is the normal locked position.

Each of the locks is attached to the rear side of a door 33 (Fig. 29), as the door of a safe-deposit box for example, and is adapted to be operated by an intermediary in the nature of a compound key which is temporarily assembled with it on the front of its

door and which receives the operating key or keys. For this purpose each lock is provided with a sleeve 52 on its cap which extends through the door (Figs. 1 and 2), and is concentric with the axial line of the parts 41, 47 and 48 and adapted to receive that part of the intermediary which operates the lock as shown in Fig. 2. The intermediary may be of any form suitable for the purpose intended, and in the present embodiment consists of a compound key which comprises a case 53 and a cap 54, connected by suitable screw-bolts (not shown). A shaft 55 is journaled at its front end in the cap 54, and its rear end projects out beyond the back of the case of the compound key and is adapted to pass through openings in the sleeve 52 and the parts 41, 47, 48 and 49 into a seat 56 in the inner face of the rear side of the case 30 when the compound key is assembled on the lock, as shown in Fig. 2.

The shaft is provided near its rear end with a collar 57 fixed thereto, which is irregular in contour or shape, being hexagonal in the form shown in the drawings, the openings in the parts 41, 47, 48, and 52 being of corresponding size and shape to allow this collar to pass therethrough to seat in a corresponding opening in the gear 49 when the compound key is employed, as shown in Figs. 2, 12 and 18. The shaft is provided near its front end with a gear 58 lying against the cap 54. Between the collar 57 and the gear 58 a plurality of concentric sleeves 59, 60 and 61 are mounted upon the shaft one within the other, as shown in Figs. 1 and 2, one for each tumbler and the bolt-gears of the lock.

Each sleeve is provided on its rear end with a collar 62, 63 and 64, respectively, corresponding in size and shape with collar 57, and forming therewith a battery of collars adapted to be alined to pass into and out of the lock and to be reciprocated to operate the latter. As shown at 65, 66, 67 and 68 in Fig. 1, the openings in the parts 41, 47, 48 and 49 respectively correspond in shape and size with the collars, and when the gatings 50 are in locked position (Fig. 4) these irregular openings register in axial direction to receive the alined battery of collars, the arrangement being such that the collar 57 seats in the opening 68 of the gear 49, as shown in Figs. 12 and 18, the collar 62 in the opening 67 of the gear 48 as shown in Figs. 11 and 17, the collar 63 in the opening 66 of the gear 47 as shown in Figs. 10 and 16, and the collar 64 in the opening 65 of the gear 41, as shown in Figs. 9 and 15, the assemblage being represented in its entirety in Fig. 2.

The sleeves 60 and 61 which operate the tumblers of the lock by their collars are operated by tumblers in the compound key and which in the present embodiment con-

sist of pivoted spur-gear spring-pressed levers and circular parts consisting of gears fixed to the ends of the sleeves opposite the collars. As shown in Figs. 1, 2, 6 and 7, 5 the inner sleeve 61 has a gear 69 next to the gear 58, and the next sleeve 60 has a gear 70 next to and of the same size and character as the gear 69. Each of the circular parts 69 and 70 is operated by a pair of 10 levers, one of which is operated by the customer's or depositor's key and the other by the guard's key. As shown in Figs. 6 and 7 the guard's levers or tumblers 71 and 72 are pivoted at 73 in one end of the case 53, 15 being spring-pressed by the springs 74 as shown and are adapted to be turned on their pivots by the operation of the guard's key 75 which enters a key-hole in a key-hub 76, which is provided with a semi-circular disk 20 77 co-acting with a stop 78 in the case to restrict the movement of the guard's key to a half-turn, as shown in Figs. 3 and 8. The levers 71 and 72 are provided at their free ends with segmental racks to coöperate with 25 the gears 69 and 70 respectively, to rotate the sleeves 60 and 61 and operate the collars 62 and 63 which when the compound key is in place in the lock coöperate with the correspondingly shaped openings 66 and 67 of 30 the parts 47 and 48 of the tumblers of the lock to move the tumblers to unguarded position, as shown in Figs. 10 and 11. The guard's key-hub normally stands in the position shown in Fig. 3, and when the 35 guard's key is given a half turn to the position of Figs. 5, 6, and 7, its bittings will operate the tumblers 71 and 72 to move them to the positions shown in these last two figures. The customer's levers or 40 tumblers 79 and 80 are pivoted at 81 in the opposite end of the case, being spring-pressed by springs 82 and adapted to be turned on their pivots by the operation of the customer's key 83 which enters a key-hole in the key-hub 84, which normally 45 stands in the position shown in Figs. 5 to 8.

The customer's key-hub 84 has a flat face 50 85 as shown in Figs. 6, 7 and 14, and is provided with an intermittent gear 86 resting against the rear wall of the case 53 and adapted to engage with a gear 87 on the sleeve 59 to communicate motion to the collar 64 and its associated bolt-gear 41 with which the collar interlocks, as shown in 55 Figs. 2 and 15, when the compound key is in the lock. The gear 87 is located between the rear wall of the case 53 and the gear 70, and is somewhat larger than the latter.

The tumblers 79 and 80 normally rest 60 upon the flat face 85 of the customer's key-hub, as shown in Figs. 3, 6 and 7, with their teeth out of engagement with the teeth of the parts 69 and 70, and the guard's tumblers 71 and 72 normally rest with their 65 teeth in engagement with the parts 69 and

70, as shown in Fig. 3. In this position the teeth of the parts 69 and 70 are out of engagement with the teeth of the customer's tumblers 79 and 80, as shown in Figs. 6 and 7. When the guard's key is given a 70 half turn from the normal position of Fig. 3 to the position of Figs. 5 to 7 to unguard the lock, as shown in Figs. 6 and 7, the teeth of the parts 69 and 70 pass by the teeth on the customer's tumblers 79 and 80, 75 and when the customer's key is turned from the normal position of Figs. 1 and 5 to 8 to the position indicated by the character *x* in Fig. 1 the tumblers 79 and 80 are raised by the cam-action of the hub into mesh with 80 the teeth of the gears 69 and 70, it being understood that these movements of the hubs 76 and 84 are successive and that the hub 84 by its cam action on the tumblers locks the tumblers 69 and 70 in their unguarded position. Further rotation of the customer's key to the position indicated by the character *y* in Fig. 1 cams the tumblers 79 and 80 as shown in Fig. 14, and further rotates the gears 69 and 70, which by their 85 associated collars 62 and 63 rotate the two-part tumblers of the lock to aline their gatings 50 in the path of the fence 51.

The intermittent gear 86 normally occupies a position with its teeth out of engagement with the teeth of the gear 87 as shown in Fig. 3, and the rotation of the customer's key-hub 84 to the position *y* also brings the first tooth of the gear 86 into engagement with the teeth of the gear 87 (Fig. 14), and continued rotation of the key-hub in the direction of the arrows in Figs. 1 and 8 turns the sleeve 59 and its collar 64 to move the bolt-gears 41 and 40 to retract the bolt. 95

The continued rotation of the gears 69 and 70 from the *x* position to the *y* position by the customer's tumblers moves the guard's tumblers to the position shown in Fig. 14, and the gears 69 and 70 are provided with cams 88 and 89 respectively 100 which then stand in the return paths of the tumblers 71 and 72 and prevent them from snapping back under the influence of their springs 74. The cams 88 and 89 are so placed as to be beyond the extreme position to 105 which the guard's key can raise the tumblers 71 and 72, so that if the combined action of the guard's and customer's keys should move either of the gears 69 and 70 farther than the extreme position to which the guard's key alone could move them the tumblers are not moved farther as the cams merely slide over them. The cams are cut away at 90 and 91 (Figs. 6 and 7) so as to give clearance to the tumblers 79 and 80 and when these tumblers are brought into mesh with 95 69 and 70 they will not strike the cams. When the tumblers 79 and 80 mesh with 69 and 70, at the *x* position, the guard may 110 withdraw his key, and so be free to serve 115

<p

other customers while the first customer is completing the unlocking of his box. If the customer desires to temporarily lock his door, as while his inner box is out, he may 5 relock by turning his key back to the α position to shoot and lock the bolt, although it is still unguarded. By this means he can dispense with the guard's service in returning his box and unlocking his door, but as 10 the customer's tumblers are against the hub but not down on the flat-face 85 and are in mesh with gears 69 and 70 leaving their collars out of register the compound-key cannot be withdrawn. The door may then be 15 locked by the customer again turning to the α position, and before the guard can remove the compound-key he must turn the customer's hub (by any tool or the finger) to its normal position of Fig. 1, so that the flat-face 85 allows the tumblers 79 and 80 to 20 drop out of engagement with the parts 69 and 70 by the action of the springs 82 (Figs. 6 and 7), and as the guard's key is also out the springs 74 turn the parts of the tumblers 25 to their original positions to aline their collars 62 and 63 with the other collars so the compound-key may be withdrawn. The lock is then guarded and locked. If the guard turned the customer's key-hub away 30 from normal he could turn it only to the γ position as the gear 86 would then mesh with the gear 87 which is held from turning by the dis-alinement of the gatings of the lock tumblers. In relocking the customer 35 may also turn back to original position of Fig. 1, whereby the flat-face 85 of his key-hub allows the tumblers 79 and 80 to drop to the position of Fig. 3, and the springs 74 will then throw the tumblers back to normal 40 position, thereby rotating the parts to aline their collars with the other collars, thus both locking and guarding the lock, and the compound-key may then be removed.

45 The lock may be reset to coöperate with different combinations of the collars controlled by the bittings of different keys, and this resetting operation is controlled by a supplemental or manager's lock which in 50 the present instance consists of an ordinary pin-tumbler lock 92. The hub of this lock is provided with a gear 93 meshing with the gear 58 upon the end of the shaft 55, so that rotation of the hub of the manager's lock 55 rotates the collar 57 of the shaft 55 of the compound key. When the compound key is in position in the lock the shaft 55 is in its seat 56 and the collar 57 is seated in the correspondingly shaped opening 68 of the gear 60 49, as shown in Figs. 2, 12 and 18, so that rotation of the shaft rotates the gear 49 of the lock.

65 A gear 94 is journaled on trunnions 95 in the case of the lock and meshes with the gear 49, the cup 43 being cut away for this pur-

pose (Fig. 12). The front trunnion is provided with an arm 96, and the upper bolt-tail 38 is provided with a projection or stop 97 which lies in the path of the arm when the bolt is shot (Fig. 18) and prevents the 70 gear 94 from turning to the left or counter-clockwise. The front trunnion is also provided with a cam 98, which is under the arm and is adapted to coöperate with a latch 99 pivoted upon a post 100 in the case 30 to normally maintain its free end out of engagement with a lug 101 projecting laterally from the rear face of the bolt-tail 38. The rear trunnion of the gear 94 is provided with an intermittent gear 102, the tooth of which 75 meshes with a depression 103 in the arm 104 of a bell crank lever pivoted at 105 on the case 30, and whose other arm 106 carries the post 46 (Fig. 12) upon which the circular parts 44 and 45 of the tumblers are pivoted. 80 In order to reset the tumblers of the lock to coöperate with a new combination or arrangement of the collars of the compound key corresponding with bittings of a different key, such as the customer's key 107, the 85 guard's and first customer's keys 75 and 83 unlock and retract the bolt in the manner heretofore described, at which time the parts in the lock take the position shown in Fig. 19, with the projection 97 withdrawn from the path of the arm 96. The manager's key 108^a is then inserted in the lock 92 and is turned counterclockwise a third of a revolution until the arm 96 strikes a lower projection or stop 108 on the bolt-tail 38, as 90 shown in Fig. 20, this movement of the manager's lock also moving the cam 98 out of engagement with the latch 99, to allow the latter to drop upon the backwardly projecting lug 101, as shown in Fig. 20. The 95 bolt is now shot and locked by the latch 99 engaging the depression in lug 101, the parts then standing as shown in Fig. 21, leaving the manager's lock unlocked by reason of the stop 108 being projected out of the path 100 of the arm 96, and leaving the keys in the unlocked position of Fig. 14. The manager's key is now further turned counterclockwise, the projection 108 being out of 105 the path of the arm 96 to permit this movement, which brings the tooth of the intermittent gear 102 around to mesh with the depression 103 of the arm 104 of the bell-crank lever (Fig. 22), and further movement of the manager's key moves the bell-crank 110 on its pivot and thereby throws parts 44 and 45 out of engagement with the parts 47 and 48, as shown in Fig. 22, leaving the parts of the tumblers disconnected and in 115 position to be reset with relation to each other upon the bittings of a different key 107. The customer's and guard's keys 75 and 83 are now removed, although in this instance the guards key need not be removed as the re-setting is now upon a new 120 125 130

customer's key alone and the gears 47 and 48 having been returned to their normal locked position when the keys were removed, and the gears 44 and 45 being out of engagement therewith the latter are held in unlocked position by the fence engaging the gatings and upon the insertion of the guard's key and a new customer's key 107 in the compound key and turning the same to unlocked position the tumblers of the compound key are operated to correspond to the bittings of the guard's key and the new customer's key, and the gears 47 and 48 are correspondingly operated to assume a different relation with respect to the gears 44 and 45. This operation brings the gears 47 and 48 into their unlocked position, at which time the bolt-gears begin to operate on the bolt-tails which are arrested by the projection 101 striking the latch 99. The manager's key is now reversed or moved clockwise and causes the gear 102 to reverse the movement of the bell-crank and thus throw the gears 44 and 45 back into engagement with the gears 47 and 48 upon the new setting or combination, and the further turning of the manager's key brings the cam 98 into engagement with the latch 99 and raises the latter and brings the arm 96 up against the projection 97 which prevents further movement of the manager's key, the parts then being in the position shown in Fig. 23. The latch 99 being thus raised out of the path of the bolt the customer can now retract the bolt to the position shown in Fig. 24, and the continued turning of the manager's lock in clockwise direction until the key is in its withdrawal position brings the parts of the lock back to the position of Fig. 19, with the tumblers set for the bittings of the new key. The views shown in Figs. 19 to 24 are made with the parts 40, 41, 44, 47 and 48 lifted out in order to show the other parts to better advantage, the part 45 being partially cut away. While this description of re-setting the lock is made with respect to a new customer's key, it is obvious that the same may be re-set upon a new guard's key, or upon a new guard's key and a new customer's key, or upon a new customer's key alone.

While I have shown the compound key as operated by keys it is obvious that the same results may be obtained by making the gears 69 and 70 in the form of dials adapted to be hand operated, in which case the gear 87 would be turned by hand. The manager's lock would preferably remain the same.

In Fig. 29 I have shown a series of safe-deposit lock-boxes provided with the locks of this invention adapted to be operated by my new compound key. Each lock is preferably set for a different customer's key, but all are operated by the intermediary. The locks are as shown upon the rear wall of the

doors, one of the boxes being open in this figure to illustrate this fact, and the intermediary is assembled to coöperate with the locks when the doors are closed by inserting the shaft and collars into the lock sleeve, projections 109 on the face of the door taking into suitable openings in the case of the intermediary to steady the latter in position. The intermediary is a compound key in that it comprises a plurality of parts to operate the locks such as a part to operate the bolt of the lock and a part to operate the tumbler or tumblers of the lock, and also a part, such as the manager's lock, to control the re-setting operation in cases where the locks are adapted to be re-set for different keys.

Safe-deposit locks as now usually constructed have multiple key locks, one key for each depositor and a common key for the guard, and each lock therefore is of necessity provided with a guard's portion in addition to its customer's portion. By employing my invention I am able to eliminate all these guard's portions from all the locks, and unite the guard's portion in a single device. Similarly where the locks as now constructed are adapted to be reset for different keys, they must either be removed to be reset or each must have within it the means (such as a latch or a supplemental manager's lock) to control this re-setting; by my invention in its more extended application I obviate the necessity of removing the locks in the one case and eliminate the manager's locks with latches from all the locks in the other case, and unite this supplemental lock for all the locks in a single device. It is obvious that the elimination of all these guard's portions from the locks reduces the essential parts to a minimum while retaining all the advantages of the multiple key-locks, and similarly the elimination of all the manager's locks or the latches reduces the parts to a minimum while retaining all the advantages of controlling the resetting for different keys by a third party, as the manager. The intermediary is a unitary structure for the guard's portions of a series of multiple key-locks instead of multiplying these guard's portions throughout all the locks; and also in its more extended use as described is a unitary structure for the manager's locks controlling a series of locks in resetting for different keys instead of multiplying these manager's locks throughout all the locks.

By this invention the lock cannot be left unguarded as the intermediary cannot be removed until the lock is guarded, and as the guard retains custody of the intermediary it follows that the unguarded condition existing while the intermediary is in the lock is made apparent by the presence of the intermediary in the lock.

Having described my invention what I claim as new and desire to secure by Letters Patent is—

1. A series of locks set to different combinations, and an intermediary adapted to be set to the different combinations to interchangeably lock and unlock each of the locks. 70
2. A series of locks set to different combinations, and a key-operated intermediary adapted to be set to the different combinations to lock and unlock each of the locks interchangeably. 75
3. A series of doors each having an opening and a lock attached on its rear face, the locks being set to different combinations, and an intermediary adapted to be interchangeably assembled on the front face of each door to lock and unlock the associated lock. 80
4. A series of doors each having an opening and a lock attached on its rear face, the locks being set to different combinations, and a key-operated intermediary adapted to be interchangeably assembled on the front face of each door, and having means to extend through the door to coöperate with the associated locks. 85
5. A series of doors each having a lock, and a key-operated intermediary adapted to be temporarily attached to each door and operate each lock. 90
6. A series of locks set on different keys, and a compound key adapted to operate any of the locks by any of a plurality of keys on which the respective lock is set. 95
7. A series of locks and a compound key adapted to operate each of the locks and operated by depositor's and guard's keys. 100
8. A series of locks set on different keys and each adapted to be reset, and a compound key to operate the locks and adapted to be operated for operating and re-setting any of the locks. 105
9. A series of locks, a plurality of keys, and an intermediate device adapted to be operated by any of the keys to transmit action to the locks. 110
10. A series of locks, a plurality of keys, and an intermediate device adapted to be temporarily assembled with each lock to transmit the key-action to the associated lock and to be operated by any one of the keys. 115
11. A lock having a bolt and tumblers, a key, and an intermediary operated by the key to control the tumblers and bolt. 120
12. A lock having a bolt and tumblers, a series of keys, and an intermediary operated by the keys to control the tumblers and bolt. 125
13. A lock having a bolt and a series of tumblers therefor adapted to be reset for different keys, and a multiple-key intermediary adapted to operate the lock by any of a plurality of keys on which the lock is set. 130
14. A lock having a bolt and a series of tumblers therefor adapted to be reset for operation by different keys, and a multiple-key intermediary adapted to operate the lock by any of a plurality of keys on which the lock is set and having a supplemental lock to control the re-setting of the first lock. 70
15. A lock having a series of two-part tumblers, means for re-setting the parts in new relations, a bolt controlled by the tumblers, a multiple-key intermediary adapted to operate the tumblers and bolt, and a supplemental lock on the intermediary for controlling the re-setting means. 75
16. A lock having a series of two-part tumblers, means for re-setting the parts in new relations, a bolt controlled by the tumblers, a multiple-key intermediary adapted to operate the tumblers and bolt, means in the intermediary to operate the re-setting means and to lock the same in reset position. 80
17. A lock having a plurality of two-part tumblers the respective parts of which are constructed to be reset for different combinations, means for re-setting the said tumblers, and an intermediary having means to operate and reset the lock and a supplemental lock for locking the said re-setting means. 90
18. A lock having a plurality of two-part tumblers the respective parts of which are constructed to be reset for different combinations, of an adjusting means for re-setting the said tumblers, and an intermediary having means to operate and reset the lock and a supplemental lock for locking the said adjusting means. 95
19. A lock having a plurality of two-part tumblers the parts of which are separable to be set for operation by different combinations, means coacting with all of the two-part tumblers for simultaneously moving one part of each tumbler with respect to the other part thereof, so as to unlock the two parts of each tumbler, and then restore the parts of each tumbler to their locked positions after one part of each tumbler has been set for a different key, and a compound-key having means to operate and reset the lock and a supplemental lock for locking the resetting means aforesaid. 100
20. A lock having a plurality of two-part tumblers the parts of which are separable to be set for different combinations, of an adjusting device coöperating with all of the tumblers for simultaneously separating their parts to permit them to be reset and simultaneously restoring their parts to their normal positions, a compound-key adapted to be assembled on the lock, means in the key coöperating with the tumblers to operate the lock, and a supplemental lock located in the compound key and connected with the said adjusting device whereby the latter is operated. 105

21. A lock having a bolt and tumbler-mechanism adapted to be reset for different combinations, and an intermediary adapted to operate and reset the lock.
- 5 22. A lock having an opening, a bolt-gear and two part tumbler, means to connect and disconnect the parts of the tumbler, a gear operating said means, said gear, bolt-gear and one part of said tumbler being alined 10 with said opening, a compound key having projections adapted to enter said openings to coöperate with said gear, bolt-gear and tumbler, and means to operate said projections.
- 15 23. A lock having an opening, a bolt-gear and tumbler having openings alined with said lock opening, and a compound key having projections adapted to enter said openings to coöperate with said gear and 20 tumbler, and means to operate said projections.
- 25 24. A lock having an opening, a bolt-gear and two-part tumbler, means to connect and disconnect the parts of the tumbler, a gear operating said means, said gear, bolt-gear and one part of said tumbler having irregular 30 openings alined with said lock-opening, and a compound-key having a shaft provided with a collar adapted to enter the opening in said gear to operate the same, sleeves on the shaft having collars adapted to enter the openings in said bolt-gear and tumbler, and means to move the shaft and sleeves.
- 35 25. A lock having a sleeve, a bolt-gear and two-part tumbler, a lever carrying one part of said tumbler, a gear to operate the lever to connect and disconnect the tumbler parts, said gear, bolt-gear and one part of 40 said tumbler having irregular openings alined with said sleeve, and a compound-key having a shaft adapted to pass into said sleeve and having a collar corresponding to and adapted to enter the opening in 45 said gear, sleeves on the shaft having collars corresponding to and adapted to enter the openings in said bolt-gear and tumbler-part, means to operate the sleeves, and a lock on the said compound-key controlling said 50 shaft.
26. A lock having a sleeve, a bolt-gear and two-part tumbler, a lever carrying one part of said tumbler, a gear to operate the lever to connect and disconnect the tumbler 55 parts, said gear, bolt-gear and one part of said tumbler having irregular openings alined with said sleeve, and a compound-key having a shaft adapted to pass into said sleeve and having a collar corresponding to 60 and adapted to enter the opening in said gear, sleeves on the shaft having collars corresponding to and adapted to enter the openings in said bolt-gear and tumbler-part, gears on said sleeves and shaft, key- operated tumblers coöperating with said 65 gears, and a lock controlling said shaft-gear.
27. A lock having a sleeve, a bolt-gear and two-part tumbler, a lever carrying one part of said tumbler, a gear to operate the lever to connect and disconnect the tumbler 70 parts, said gear, bolt-gear and one part of said tumbler having irregular openings alined with said sleeve, and a compound-key having a shaft adapted to pass into said sleeve and having a collar corresponding to 75 and adapted to enter the opening in said gear, sleeves on the shaft having collars corresponding to and adapted to enter the openings in said bolt-gear and tumbler-part, gears to operate the sleeves, multiple-key 80 tumblers to operate the gears, and a lock for said shaft.
28. A lock having a sleeve, a bolt-gear and series of two-part tumblers, parts of the tumblers being pivotally mounted and 85 adapted to be locked in engagement with the other tumbler-parts in a variety of different relations, means for simultaneously moving one part of each tumbler to connect and disconnect the parts thereof, a gear for moving said means, said gear, bolt-gear and one part of each tumbler being alined with said sleeve, a compound-key having a shaft to move said gear and sleeves to move said bolt-gear and tumblers, a guard's key 90 and a customer's key to move said sleeves, and a manager's key to move said shaft.
29. A lock having a bolt, a bolt-gear and two-part tumbler, a lever on which one part of said tumbler is mounted, a pivoted latch, 100 a gear adapted to move the lever, a cam on the gear to move the latch, an arm on the gear, stops on the bolt-tail, a second gear to operate the first gear, means to operate the second gear to disconnect parts of the 105 tumbler and then connect them in reset relation, and means to operate the bolt-gear.
30. In a lock the combination with a bolt and a two-part tumbler, of means to reset the tumblers for different combinations, 110 said means being locked by shooting the bolt.
31. A series of locks each adapted to be set on different combinations, and a compound key having depositor's and guard's 115 key mechanism to selectively operate the locks and having a supplemental lock controlling the resetting of the locks.
32. The combination with a multiple-key controlled lock, of an intermediary having 120 devices operated by guard's and customer's keys to unguard and operate the lock, the arrangement being such that the lock may be relocked while unguarded or relocked and reguarded by the said customer's key. 125
33. A series of locks set to different combinations, an intermediary adapted to lock and unlock each of the locks, and a plural-

ity of keys for the intermediary one of which is peculiar to one of said locks and one of which is common to all said locks.

34. A series of locks set to different combinations, an intermediary adapted to lock and unlock each of the locks, a plurality of keys for the intermediary one of which is peculiar to one of said locks and one of which is common to all said locks, and a

key-controlled lock in the intermediary 10 controlling the resetting of the locks.

In testimony whereof I affix my signature in presence of two witnesses.

BRUCE BORLAND.
